UNITED STATES PATENT OFFICE

LAZURUS W. POLLACK, OF BROOKLYN, NEW YORK

DOLL'S EYES AND MOUNTING THEREFOR

Application filed March 16, 1930. Serial No. 347,645.

This invention relates to artificial eyes for dolls, or other figures, and means for mounting the eyes within the heads of dolls in a superior manner.

- 5 One of the objects of the invention is to provide a mounting for dolls' eyes which may be readily inserted and anchored within the head, and will be adjustable to heads of different sizes.
- 10 Another object of the invention is the provision of means for supporting the eyes upon a hanger or support in such manner as to provide for vertical and horizontal adjustment of the eyes to suit the eye openings in 15 the face of the doll.

Another object of the invention is to provide dolls' eyes with a novel form of weight for causing the eyes to open and close in response to changes in position of the doll's 20 head.

Another object of the invention is to provide a simple and economical form of blank for dolls' eyes having means for sustaining the eyelashes in position.

25 Other objects and important features of the invention, including novel combinations of parts and details of construction, will more fully appear from the following description, when considered in connection 30 with the accompanying drawings in which:

Fig. 1 is a view in front elevation illustrating a doll's head to which the invention is applied;

Fig. 2 is a vertical sectional view on the 35 line 2—2 Fig. 1;

Fig. 3 is an enlarged view in front elevation showing the hanger with the eyes supported thereon;

Fig. 4 is a transverse section on the line 40 4—4 Fig. 3;

Fig. 5 is a view in side elevation of the hanger and eyes as shown in Fig. 3;

Fig. 6 is a transverse sectional view of a 45 doll's head illustrating a modified construction;

Fig. 7 is a sectional view on the line 7—7, 50 Fig. 6.

Fig. 8 is a detail view showing the blank 55 from which the weight, eyes and eyelids are fashioned;

Fig. 9 is a front elevation of the eyes and their support as formed of the blank shown in Fig. 8; and

Fig. 10 is a sectional view on the line 10—10 Fig. 9.

Referring first to Figs. 1 to 5, inclusive, a doll's head A is provided interiorly with a mass of material 2 which serves as an anchoring element for the hanger 3. The hanger 3 is composed of flexible sheet metal, having its upper extremity provided with one or more prongs or forks as 4—4 which are adapted to be embedded in the material 2 and its lower extremity 5, which may be upwardly bent to embrace the lower forward edge of the doll's head, whereby said hanger may be anchored to the doll's head. The hanger, as will be seen, is suitably bent to follow interiorly the configuration of the face of the doll, as shown in Fig. 2. As herein shown, the hanger is made of channel bar form (see Fig. 4) in order to suitably stiffen the same. An adjustable, 60 slideable support 6 is preferably composed of a piece of sheet metal which is folded over upon itself to enclose the hanger 3, as shown at 7, Fig. 5, the support 6 having bifurcations 8 which are provided at their extremities with looped or folded over portions 9, which enclose, and slide freely upon spaced prongs 10, there being sufficient frictional resistance be- 65

tween the parts to hold the support in any position of adjustment on the prongs 10 to which it may be moved. The prongs 10 are fastened by a clip 11 to a bridge or support 12, the connection of the intermediate portion 13a of the prongs to the bridge being 70 a pivotal one. The bridge 12 has preferably formed integral therewith the cups 13 which form supports for the eyes 14, the latter being shaped to fit snugly over the cups and being 75 made of porcelain or other material which is colored to represent the eyes in any usual or preferred manner.

Extending downwardly from the bridge 12 is an arm 15, herein shown as of sheet metal 80 and having its end portion 16 coiled a suitable number of times to provide a weight. This weight overbalances the eyes and by reason of the pivotal connection between the portion 13a of the prongs 10 and the clip 11, 85 90 95 100

the eyes when mounted as shown in Fig. 5 are free to open and close in accordance with the changes in position of the doll's head.

The hanger 3 is preferably provided with a suitable number of prongs 17 which are formed by slitting the sides of the hanger and bending the prongs outwardly therefrom. These prongs, as shown in Fig. 2, are adapted to be embedded in the material of the doll's head to aid in anchoring the hanger to the head.

The hanger 3 is herein shown as provided with a pivoted tongue 18, formed by a piece of sheet metal which is bent at 19 to form a hooked portion 20 adapted to be passed through a slot 21 in the hanger. The lower portion of the tongue 18 projects horizontally outwardly through the mouth opening of the doll's head, as shown at 22, Fig. 2, and when the head is held in a vertical or substantially vertical position with the parts assembled as shown in Fig. 2, the weight 16 will cause the arm 15 to bear against the surface 24 of the tongue 18 and project the tongue 25 through the mouth opening.

The hanger 3 is also provided with groups of punched out indentations 3a, 3a, which may be pressed against the interior of the doll's head, to aid in firmly anchoring the hanger in position. Teeth 23 are formed by pressing out a portion of the metal of the hanger and are suitably whitened. These teeth form in connection with the tongue 22, natural features of the doll's head and are adjusted in position opposite the mouth opening so as to appear in their proper positions when the hanger is inserted.

By moving the support 6 along the hanger vertically when the head is in normal position, the eyes will be moved bodily for vertical adjustment so that they may be brought into alignment with the eye openings in the face, thereby being adjustable to dolls' heads having eye openings having different locations therein. The eyes are furthermore adjustable towards and from the eye openings in the face in a horizontal plane by movement of the forked members 10 in the loops 9 of the support 6 so as to locate the eyes in a vertical plane which will be appropriate for the eye openings in different sized heads. It will thus be seen that with a device as described, the eyes are capable of vertical as well as horizontal adjustment, thereby being adaptable for dolls' heads of various sizes and wherein the eye openings are located in various positions, and being retained in adjusted positions by frictional engagement between the parts.

In the construction as illustrated in Figs. 6 and 7, I provide, in lieu of the hanger 3, a bridge 30, comprising a piece of sheet metal, preferably with upturned edges 31, thereby providing a channel form of bridge with its attendant properties of resisting bending

strains. The bridge is provided at its opposite ends with inclined portions 32, and has on opposite sides of its center two outwardly projecting guide tubes 33, one of which only appears in Fig. 6. These tubes receive slidably the two limbs of the forked carrier 10a, which is constructed like the forks 10—10 for hingedly supporting the eyes, as shown in Fig. 4.

The forked member 10a is held by a clip 11a to the bridge 12, the same as is shown in Fig. 4, and the eyes are adjustable in a horizontal plane by sliding the forks 10a in the tubes 33. The device as illustrated in Figs. 6 and 7 is also provided with a downwardly extending sheet metal arm 15 which has its lower extremity coiled to form a weight 16, as in the construction first described. In the embodiment as illustrated in Fig. 6 and Fig. 7 of the drawings, provision is made for a horizontal adjustment but not for vertical adjustment of the eyes.

Referring to Figs. 8, 9 and 10 of the drawings it will be seen that the eye cups, as 13, are formed integrally with the central member or bridge 12 from which latter extends the weight-carrying arm 15. Eyelid portions 40, 40, are connected by necks 41 with the cup portions 13, and such eyelids are adapted to be folded over upon the cups 13, with the eyes 14 enclosed between the eyelids 40 and the cups 13, while eyelashes 42 are also arranged between the folded over portions 40 and the eyes 14, whereby the lids 40 serve as clamping members both for the eyes 14 and the eyelashes 42. The lids 40 are provided with tabs 40a which may be bent over the cups 13 to retain the lids in clamping relation to the cups. This is an important feature of my invention, as it permits the stamping out in a single operation of a blank in which the eye supporting cups, the bridge, the eyelids and the arm and weight for operating the eyes are all formed from a single piece of metal.

In the use of the mounting for the eyes shown in Figs. 6 and 7 when the eyes with the forked member 10a are assembled by the insertion of the forks in the tubes 33, the bridge piece 30 is passed into the head through the lower opening therein in an inclined position, and when the eyes are properly located opposite the eye openings 50, the bridge 30 is turned in the direction indicated by the arrows in Fig. 7, which causes the pointed ends 51 of the bridge to be embedded in the material of the doll's head, thereby anchoring the eyes in position within the head. This is a very simple manner of mounting the eyes within the head, and may be performed rapidly, which is quite desirable in devices of this kind where quantity production and assembly are important factors in the manufacture thereof.

The right is reserved to make such changes

in the details of construction or in the arrangement of the parts illustrated as are contemplated by the spirit of the invention, provided such changes and modifications do not depart from the scope of the following claims.

What I claim as my invention is:

1. In a device of the class described, the combination of a hanger of flexible material arranged to be inserted in a doll's head and having means at its upper end for anchoring in the top portion of the head, and its lower end bent forwardly and enclosing the lower edge of the doll head, and doll's eyes movably supported from said hanger.

2. In a device of the class described, a flexible sheet metal hanger arranged to be inserted within a doll's head, means for anchoring said hanger at its opposite ends to said head, a slidable support provided with means for frictionally gripping said hanger to provide for vertical adjustment thereof, and a pair of eyes sustained from said support.

3. In a device of the class described, a hanger of flexible material arranged to be inserted in a doll's head, a slidable support having means to frictionally engage the hanger for vertical adjustment thereof, eyes carried by said support, and means sustaining said eyes on the support and constructed and arranged for horizontal adjustment backwardly and forwardly towards and from the eye openings.

4. In a device of the class described, the combination of a hanger of flexible material arranged to be inserted within a doll's head, a support enclosing said hanger and vertically slidable thereon, a bridge mounted for adjustment in a horizontal plane on said support, and dolls' eyes pivotally mounted on said bridge.

5. In a device of the class described, the combination of a flexible hanger arranged to be inserted within the doll's head and to be anchored at opposite ends thereof, a support embracing said hanger and movable vertically thereon, guideways carried by said support and angularly arranged to said hanger, a forked member sliding in said guideways and eyes pivotally connected with said forked members.

6. In a device of the class described, a flexible hanger made of sheet metal of channel form and arranged to be mounted within a doll's head, means for anchoring the opposite ends of said hanger to said head, a supporting member formed of doubled over metal and arranged to embrace said hanger and slidably mounted thereon, guide eyes carried by said support, a forked member entering said guide eyes and movable therein in a horizontal plane when the head is in normal position and eyes pivotally connected with said member.

7. In a device of the class described, the combination of a hanger arranged to be mounted within a doll's head, anchoring means at opposite ends of the hanger for holding the same in position, a slidable support movable longitudinally of said hanger and provided with guiding means at right angles to the hanger, a forked member engaging said means and slidable therein, eyes pivotally connected with said member, and a sheet metal arm extending downwardly from said eyes and having its end coiled to provide an operating weight therefor.

8. In a device of the class described, the combination of a hanger, a support movable longitudinally thereon, eye-supporting means adjustable in said support at right angles to the direction of movement of said support on said hanger, a tongue pivotally mounted in the doll's head, an arm extending downwardly from said eyes and arranged to bear upon said tongue.

9. A blank for making doll eyes comprising spaced circular portions to support the eyes, segmental eyelid portions attached by narrow necks to said circular portions, an intermediate support or bridge and a downwardly extending member to form the weight and arm.

10. In a set of doll's eyes, the combination of a bridge, concave portions supported in spaced relation from opposite sides of said bridge, and eyelid portions connected by narrow pieces of material with said concave portions.

11. In a set of doll's eyes, the combination of a bridge, spaced concave eye supporting portions connected with opposite sides of said bridge, integrally connected eyelids attached to said concave portions, said lids being adapted to be bent over upon the upper portion of the concave portions and with said portions to embrace the eyes and eyelashes.

12. In a device of the class described, a hanger for supporting dolls' eyes comprising a strip of sheet material having means for anchoring it within the head, a portion of the material of the strip being bent outwardly from the body and shaped to resemble teeth, and dolls' eyes adjustably supported by said strip.

13. In a device of the class described, a hanger for supporting dolls' eyes comprising a strip of sheet material provided with means for anchoring it within the head and having a slot therein, a portion of said strip being bent outwardly and shaped to resemble teeth and a tongue pivotally sustained from said strip and arranged to be projected through said slot.

In testimony whereof I have hereunto set my hand this 11th day of March A. D. 1929.

LAZURUS W. POLLACK.
